UNITED STATES PATENT OFFICE.

THOMAS P. WRIGHT, OF TORONTO, ONTARIO, CANADA, ASSIGNOR TO JOHN D. RIPSON,
OF ROCHESTER, NEW YORK.

WATER MOTOR.

Application filed February 28, 1925. Serial No. 12,442.

The principal objects of this invention are to enable the motor being used under varying conditions of water levels to produce maximum power; and to allow of the ready removal of the motor from danger of ice or other floating objects liable to injure the same.

A still further object is to produce a wheel of extremely light but rigid construction.

The principal feature of the invention consists in the novel arrangement of a wheel journal and support carried upon an inclined support, whereby the carriage may be moved up or down the incline to regulate the position of the lower part of the wheel in relation to the water; and whereby the rotation of said wheel is transmitted to the power mechanism at whatever position it may be held.

A further important feature consists in the novel manner of pivoting the blades and interconnecting the same to effect the mutual support between the blades and to lighten the construction.

In the drawings, Figure 1 is a side elevational view of my improved form of water wheel with part of the frame and carriage broken away showing the machine for transmitting the power.

Figure 2 is a plan view, a portion of the wheel vanes being broken away.

Angularly placed water motors arranged to dip the lower side of the wheel into a running stream have been proposed but while the means have been provided for withdrawing such motors from the water in case of danger of damage from ice, under such conditions the wheel is withdrawn from service but no provision has been made for maintaining the wheel in service at various water levels.

According to the present invention a frame 1 is erected upon the edge of the bank of a stream, said frame having an inclined trackway 2 on the upper side, which trackway is here shown projecting beyond the lower end of the frame.

Upon the trackway 2 is slidably arranged a carriage 3 adapted to slide thereon and upon this carriage is mounted the water wheel base 4.

The carriage is supported by the cable 5 which extends upwardly of the trackway and secured to the sheaves 6 at the top in-

ner end of the frame. A double notched and pawl arrangement 7 is securely fastened to one side of the frame and through its operation the sheave 6 is rotated to wind the cable and move the carriage on the trackway to any desired position.

The wheel base 4 is provided with a plurality of bracket members 8 radially arranged and in each of these bracket members is pivotally secured a wheel vane 9. The vanes are formed of light sheet metal having reinforcing bars 10 and 11 at the top and bottom edges, the inner ends of which are secured in a casting 12 which is provided with a flat portion 13 adapted to extend between the jaw portions 14 of the bracket members 8. The outer ends of the vanes are turned at an angle to the main body in order to receive the maximum of pressure of the water. Each vane has secured thereto adjacent to the outer end and about midway of its height a double lug 15 provided with a hole at each side of the vane. Tie-rods 16 extend between the lugs 15 being hooked into the lugs and secured by suitable cotter pins.

A hub 17 projects perpendicularly from the centre of the wheel base 4 and carries a disc 18 at the top and from this disc extend the radial supporting wires 19 which are connected to the vanes 9 at the upper edge close to the outer end. These upper wires form additional supports to the vanes and relieve the strain of the weight of the vanes from the inner ends.

It will be seen that by the pivotal arrangement of the vanes described a perfectly flexible wheel is produced so that in the event of any one of the vanes coming into contact with a floating object the vane will swing upwardly on its pivot without injury to the wheel; and the entire wheel being interconnected by the tie rods 16 is rigidly supported.

A shaft 20 extending through the hub 17 of the wheel base 4, which is securely fastened thereto, is provided with a bevel gear 21 at its lower end. A shaft 22 having a key way 23 is rotatably supported in bearings 24 and 25 connected to the frame 1 and has secured to its inner end a bevel gear 26. A bevel gear 27 is securely held from rotation on the shaft 22 by a suitable feather key arranged in the hub 29 of the gear and sliding in the keyway 23 of the shaft. The

gear 27 meshes with the gear 21 and the shaft is rotated by the rotation of the wheel. The bevel gear 26 supported on the upper end of the shaft 22 meshes with a gear 30 carried on the shaft 31. This shaft 31 is supported in bearings 32 and 33 connected to the frame 1 and is provided with a pulley 34.

The power developed by the wheel in contact with the running water is imparted to the shaft 22 through the bevel gears 21 and 26 and this power is transmitted to the shaft 31 and it is taken from the shaft 31 by a suitable belt operating on the pulley 34. The power developed is preferably utilized to drive a suitable electric generator or of course it may be used direct by any suitable form of machine.

It will be seen that as the level of the water in the stream rises or recedes the wheel may be moved correspondingly upon the inclined trackway so as to maintain a most effective contact with the water or it can be entirely withdrawn from the water in the event of danger to the structure. If desirable the frame 1 may be arranged on skids so that it also may be withdrawn from a danger zone.

The construction described is extremely simple and produces the required result in a most effective manner.

What I claim as my invention is:—

1. A water motor, comprising a frame having an inclined trackway, journal bearings fixedly mounted at the upper and lower

ends of said frame centrally of its width, a shaft journalled in said bearings and having a longitudinal key-way, a carriage movably supported on said frame, a water wheel having a central shaft perpendicularly journalled on said carriage, a bevel gear secured to the lower end of said wheel shaft, a bevel gear slidably mounted on the longitudinal shaft supported in said frame, and supported by said carriage in mesh with the bevel gear mounted on the wheel shaft and adapted to travel with said carriage in sliding engagement with said longitudinally keyed shaft, and means for transmitting power from said longitudinal shaft.

2. A water motor, comprising, a rotatable member having a plurality of bracket members radially arranged, a plurality of vanes each formed with light sheet metal and having its ends pivoted in said lugs and adapted to swing upwardly, a shaft fixed in the axis of said rotatable member and extending upwardly, a plurality of flexible wires connected to said shaft and having their outer ends connected one to each of said vanes to support the weight of said vanes, flexible interconnecting rods arranged between said vanes, a carriage supporting said wheel, an inclined trackway supporting said carriage, means for moving said carriage on said trackway, and means for transmitting the power developed by said wheel in various positions.

THOMAS P. WRIGHT.
